UNITED STATES PATENT OFFICE.

ARTHUR J. AEWINE, OF NEW YORK, N. Y., ASSIGNOR TO GILLIS & GEOGHEGAN, OF NEW YORK, N. Y., A FIRM.

PORATABLE HOISTING APPARATUS.

Application filed February 2, 1921. Serial No. 441,733.

To all whom it may concern:

Be it known that I, ARTHUR J. AEWINE, a citizen of the United States, residing in the city of New York, borough of Manhattan, in 5 the county and State of New York, have invented a certain new and useful Improvement in Portable Hoisting Apparatus, of which the following is a specification.

The invention relates to portable hoists 10 and more particularly to wheeled trucks adapted to support hoisting and other mechanisms, and the object of the invention is to provide a truck which shall offer the required extended base for supporting the hoisting 15 apparatus and its load reliably, and also permit the truck with its hoist to be moved through relatively small openings, as factory doors or the like, and which shall be simple in construction, easily operated, and eminently strong and serviceable.

The invention consists in certain novel features and details of construction and arrangement by which the above and other objects are attained, to be hereinafter 25 described and claimed.

The accompanying drawings form a part 30 of this specification and show an approved form of truck with a hand-operated hoisting machine of the crane type mounted thereon.

Figure 1 is a side elevation of the truck 35 and hoist.

Figure 2 is a sectional plan view, the plane of section being indicated by the line 2-2 in Figure 1.

Figure 3 is a horizontal section, partly in 40 plan view, taken on the line 3-3 in Figure 1.

Figure 4 is a central vertical section through the main portion of the truck, certain parts being shown in elevation.

Referring to the drawings, 1 is the tubular 45 standard of a hoisting machine, having a strut or crane 2 and winch 3 by which a load suspended from the hook 4 may be raised or lowered by the cable 5 through the operation of the crank 6 as will be understood. The hoisting mechanism carried by the standard may be of any approved type.

The truck on which the hoist is mounted 50 comprises two horizontally arranged plates or disks 7 and 8 one above the other, separated by tubular sleeves or distance-pieces 9 inclosing bolts 10 extending vertically through the disks and rigidly joining the latter. On the upper disk 7 is a vertical hollow post 11 inclosing the lower end of the

standard 1 which extends through both disks and is supported, with freedom to revolve, on a step formed by a plate 12 bolted to the under face of the disk 8 and providing a recess for the reception of the lower extremity of the standard.

Between the disks at four equally spaced points circumferentially, and near the standard 1, are pivoted four radially extending arms 13 each equipped at its outer end with a caster 14 arranged to swivel on a horizontal ball-bearing at 15 and thus support the disks and hoist while permitting the whole to be rolled easily in any direction by a handle 16 attached to one of the arms, or 70 by any suitable means.

The arms are of sufficient length to afford the required large base area when positioned at right angles to each other and they are held in this position each by a pin 17 inserted through a hole in the upper disk 7 and into a corresponding recess in the upper face of the arm, and the movement of each arm in assuming this extended position is limited by a stop 18 on the under face of the 80 upper disk, struck by the side of the arm. The stops 18 are shown as lugs cast integrally with the disk 7.

In this extended condition the hoisting operations may be safely performed and the 85 truck with its hoist and load may be rolled from one position to another on the casters 14 as required.

When it is necessary to move through narrow openings, as through a door leading 90 from one section of the shop or factory to another, the pins 17 are withdrawn and the opposite pairs of arms swung away from their stops 18 toward each other into the collapsed or narrowed position shown in 95 dotted lines in Figure 3, in which they strike against similar stops 19, with their recesses in coincidence with holes 20 in the upper disk, and are held in such narrowed positions by re-inserting the pins 17 in the holes 20. 100 Thus conditioned the whole may pass through any opening of a width greater than the diameter of the disks, and the arms again extended at right angles for further hoisting operations.

The vertical depth of the arms is preferably but little less than the space between the disks, so that the inner ends of the arms are stiffly supported and the rigidity of the structure assured while permitting the 110

arms to be swung to the limited extent required.

If the door-opening is sufficiently wide only one of each pair of arms need be swung toward its mate and locked in such shifted position.

Other means than the hollow post 11 and plate 12 may be employed to support the hoist with liberty for the latter to be revolved in swinging the load; the arrangement shown is preferred as affording the desired long rigid vertical bearing for the standard 1.

Although the invention is shown and described as applied to a hoist having a rotatable standard, it will be understood that the improved truck may be employed to support other types of hoists, or with other mechanisms to which it may be adapted.

20 I claim:—

1. In a hoisting apparatus, two disks disposed horizontally one above the other, means for rigidly joining said disks and holding them spaced apart, a tubular post on the upper disk adapted to receive the cylindrical standard of a hoisting mechanism, arms pivotally mounted at their inner ends between said disks and movable horizontally, and casters on the outer ends of said arms.

2. In a hoisting apparatus, two disks disposed horizontally one above the other, means for rigidly joining said disks and holding them spaced apart, a centrally located tubular post on the upper disk, and the lower disk having a centrally located aperture, a plate on the under face of said lower disk closing such aperture, a cylindrical standard extending through said post and aperture and supported on said plate, hoisting mechanism on said standard, arms pivotally mounted between said disks, and casters on the outer ends of said arms.

3. In a hoisting apparatus, two disks disposed horizontally one above the other, means for rigidly joining said disks and holding them spaced apart, means for sup-

porting the standard of a hoisting mechanism on said disks, arms pivotally mounted at their inner ends between said disks and 50 arranged to swing horizontally, stops arranged to limit such swing, and casters on the outer ends of said arms.

4. In a hoisting apparatus, two disks disposed horizontally one above the other, 55 means for rigidly joining said disks and holding them spaced apart, means for supporting the standard of a hoisting mechanism on said disks, arms pivotally mounted at their inner ends between said disks and 60 arranged to swing horizontally, the uppermost disk having holes therein and each of said arms having a recess therein matching such holes, pins received in such holes and recesses for holding said arms, and casters 65 on the outer ends of said arms.

5. In a hoisting apparatus, two disks disposed horizontally one above the other, means for rigidly joining said disks and holding them spaced apart, means for supporting the standard of a hoisting mechanism on said disks, arms pivotally mounted at their inner ends between said disks and 70 arranged to swing horizontally, stops arranged to limit such swing, the uppermost 75 disk having holes therein and each of said arms having a recess therein matching such holes, pins received in such holes and recesses, and casters on the outer ends of said arms.

6. In a hoisting apparatus, a truck of the character set forth, two horizontally disposed disks rigidly joined and spaced apart, said disks being apertured to receive a vertical standard, four arms pivotally mounted 85 at their inner ends between said disks in opposite pairs with the arms of each pair arranged to swing toward and from each other, means for limiting such swing in both directions, and means for holding each arm 90 at such limit.

In testimony that I claim the invention above set forth I affix my signature.

ARTHUR J. ARWINE.
